(57) CLAIM

The ornamental design for a freezer organizer bin as shown and described.

DESCRIPTION

FIG. 1 is a top perspective view of a freezer organizer bin showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is another top perspective view thereof, showing the freezer organizer bin in a compressed configuration; and, FIG. 9 is another top perspective view thereof, showing the freezer organizer bin in an extended configuration of use with the handles in an outward facing position.

The broken lines illustrate portions of the freezer organizer bins that form no part of the claim.

1 Claim, 9 Drawing Sheets
